(57) **CLAIM**

The ornamental design for an vehicle rear taillight, as shown and described.

DESCRIPTION

FIG. 1 is a perspective view of an vehicle rear taillight;

FIG. 2 is a side view thereof; and,

FIG. 3 is a front view thereof.

The broken lines are included to show environmental structure and form no part of the claimed design. The drawings and descriptions represent the left side embodiment. The claim is also for a mirror image right side embodiment.
